UNITED STATES PATENT OFFICE.

ANTON I. SANDBO, OF ROCK ISLAND, ILLINOIS, ASSIGNOR TO SANDBO STARTER COMPANY, OF ROCK ISLAND, ILLINOIS.

ATTACHMENT FOR AUTOMOBILES.

1,179,966.

Specification of Letters Patent. Patented Apr. 18, 1916.

Application filed February 23, 1915. Serial No. 10,003.

To all whom it may concern:

Be it known that I, ANTON I. SANDBO, a citizen of the United States, residing at Rock Island, in the county of Rock Island 5 and State of Illinois, have invented certain new and useful Improvements in Attachments for Automobiles; and I do hereby declare the following to be a full, clear, and exact description of the invention, such as 10 will enable others skilled in the art to which it appertains to make and use the same.

My invention relates to attachments for automobiles and my object is to provide an attachment for the breather or oil inlet 15 pipe to prevent oil from being discharged through said pipe by the rotation of the gears in the crank casing.

A further object is to so arrange said device that the oil will readily enter the 20 crank casing through the pipe. And a further object is to so construct the device that it can be readily attached to any make of engine.

Other objects and advantages will be 25 hereinafter set forth and more particularly pointed out in the accompanying specification.

In the accompanying drawings which are 30 made a part of this application, Figure 1 is a side elevation of a portion of a crank casting, showing the housing containing the usual form of timing gear, and the manner of attaching my device thereto. Fig. 2 is 35 a vertical transverse sectional view through the inlet tube, showing my improved attachment applied thereto. Fig. 3 is a similar view taken at right angles to the view shown in Fig. 2, and Fig. 4 is a transverse sectional view as seen on line 4—4 of Fig. 3.

Referring to the drawings in which similar reference numerals designate corresponding parts throughout the several views, 40 1 indicates a casing, such as is used for housing the usual or any preferred form of timing gear used in connection with gas engines, and 2 is an inlet or breather pipe, through which oil is introduced into the casing and as the gears within the casing are rotated very rapidly, the oil is frequently 45 forced outwardly through the inlet pipe on to the fan belt, timing wires and other parts of the motor construction, thus wasting the oil, as well as injuring the fan belt, and also causing poor ignition through the 50 timing wires. To this end therefore, I in-

5 introduce into the pipe 2 a metallic clip 3, which is preferably formed from a single strip of metal and bent upon itself, as best shown in Fig. 3 of the drawings, the structure being substantially V-shaped, the edges 60 of the two upwardly extending arms 4 preferably converging toward their upper ends and said edges are provided with horizontal slits at predetermined intervals throughout the length of the arms, the lower severed 65 edge 5 of each slit being bent outwardly to form wings 6, the taper of the arms 4 being such that the outward edges of the outwardly bent sections or wings 6 will rest against the wall of the inlet pipe through- 70 out the full length of the arms. By arranging the wings in the manner shown, any oil ascending in the inlet pipe will be caught by said wings and prevented from passing out of the upper end of the pipe, 75 while any oil introduced into the upper end of the pipe, will readily pass through the slits formed in the arms and descend into the casing, and the spring tension of the clip will serve to securely hold the clip in 80 engagement with the walls of the pipe without the use of bolts or other means of securing the same.

If desired, the clip may be placed in a tube ready to be applied to the breather 85 pipe of the casing and by constructing the casing so that it will snugly fit in the breather pipe opening, it will not require bolts or other devices to hold the same in position, and in view of the length of the 90 tube, will dispose the opening therein in position for readily receiving the oil.

This device can be very cheaply constructed and quickly applied to use and by constructing the same of metal, it will be in- 95 destructible from use.

What I claim is:—

1. The combination with an oil receiving pipe, of a substantially V-shaped clip having wings thereon adapted to prevent oil 100 from ascending through said pipe.

2. The combination with an oil receiving pipe, of a clip positioned in said pipe and having outward spring tension, said clip having wings at its outer edges, said wings 105 engaging the wall of said pipe to prevent oil from ascending through the pipe.

3. The combination with an inlet pipe, of a spring actuated clip positioned in said pipe, the edge walls of the clip having a 110

plurality of slits therein, portions of the slit parts being bent inwardly to form wings, said wings engaging the wall of the pipe to prevent the passage of oil upwardly

5 through the pipe.

4. The combination with an oil receiving tube, of a clip, said clip comprising parallel-

ing arms, the edges of which are severed at intervals and parts of the severed portions

10 being formed into wings, said wings ex-
tending substantially at right angles to the

trend of the arms and having their edges engaging the wall of the tube whereby oil will be prevented from ascending through the tube.

In testimony whereof I have signed my name to this specification in the presence of two subscribing witnesses.

ANTON I. SANDBO.
